CAN OPENER

Henry J. Talge, Kansas City, Mo., and James B. Aberer, Mission, Kans., assignors to John C. Hockery, Kansas City, Mo., as trustee

Application August 18, 1950, Serial No. 11,826

Term of patent 14 years

(Cl. D22—2)

To all whom it may concern:

Be it known that we, Henry J. Talge and James B. Aberer, citizens of the United States, residing in Kansas City, in the county of Jackson and State of Missouri, and Mission, in the county of Johnson and State of Kansas, respectively, have invented a new, original, and ornamental Design for a Can Opener, of which the following is a specification, reference being had to the accompanying drawing, forming part thereof, in which;

Fig. 1 is an elevational view of one side of a can opener embodying our new design,

Fig. 2 is a plan view,

Fig. 3 is an elevational view of the opposite side, and

Fig. 4 is an end elevational view.

The shading illustrated in Figure 1 of the drawings is to indicate contrasting appearance.

We claim:

The ornamental design for a can opener, substantially as shown and described.

HENRY J. TALGE.
JAMES B. ABERER.
